ARTICLE HOLDING ALBUM

Lester Geis, New York, and Robert E. Pope, Seatauket, N. Y., assignors to Radio Corporation of America, a corporation of Delaware

Application February 15, 1944, Serial No. 522,510

2 Claims. (Cl. 129—20)

1

This invention relates to an article-holding album, and particularly to an album for holding comparatively fragile articles such as phonograph records, photographic plates and the like.

Albums of the character described ordinarily contain one of more article-holding units or envelopes; and once assembled, it is impossible, without destruction of the album, to alter the number of article-holding units. The album is, therefore, commercially useless for any other than the precise number of articles for which it was originally intended.

The title of the collection of articles contained in the album is ordinarily stamped on the backing member and this, again, makes the album useless for any other than the collection of articles bearing that title.

Damage is sometimes caused to fragile articles when removed from the envelopes at conventional thumb openings, by reason of the fact that the article has to be grasped firmly at such thumb opening between a thumb and a finger.

An envelope of a conventional album is ordinarily open at at least one edge and there is, therefore, nothing to prevent the entry of dust or other extraneous matter.

It is, therefore, the primary object of this invention to provide an improved article-holding album which will be free from the defects of prior art albums.

It is a further object of this invention to provide an improved article-holding album constituted by units which may be quickly and easily assembled by comparatively unskilled labor using simple equipment.

A further object of the invention is to provide an improved article-holding album in which the number of article-holding units may be varied.

A further object of the invention is to provide an improved article-holding album which may be used interchangeably for different collections of articles to be contained therein.

Another object of the invention is to provide an improved article-holding album of pleasing appearance and modern design.

A further object of the invention is to provide an improved and simply constructed article-holding unit or envelope to be contained within an album, the unit having a cover to prevent the entry of dust or other extraneous matter and to enable an article contained within the unit to be removed therefrom easily and conveniently, and without danger of damage to said article.

These and other objects are achieved in a preferred embodiment by providing an album

2

constituted by a pair of outer covers and a number of article-holding units or envelopes, secured by simple means at one edge thereof and having a fold line adjacent and parallel to that edge, as a result of which the album may be opened and closed easily. A tubular backing member for the album has flexible overlapping portions which embrace cooperative projections in the back of the album, and lock in slots or recesses formed in said back. The whole or a part of this cover may be of transparent material and an interchangeable, title-bearing slip may be inserted within the tubular member. The article-holding units or envelopes have foldable flaps formed by angularly disposed fold lines, and are treated so that they remain open when the album is open, and so that articles in the envelopes may be easily removed therefrom and replaced therein.

The invention may be better understood from 20 a consideration of the following more detailed description of a preferred embodiment thereof, when read in conjunction with the accompanying drawing, in which:

Figure 1 is a plan view of an article-holding unit or envelope contained in the album,

Figure 2 is a plan view of the backing member before referred to;

Figure 3 is an enlarged sectional view taken on the line III—III of Figure 2,

Figure 4 is an enlarged sectional view through the center of the backing member, taken on the line IV—IV of Figure 2;

Figure 5 is a bottom end view of the album; and

Figure 6 is a view in perspective of the album in open position.

Referring more particularly to the drawing, the complete album is made up of outer covers 2a and 2b, envelopes 4a, 4b, 4c, etc., and a backing member 6. For use with fragile articles, the covers may be made of cardboard or other suitable, rigid material, to the outside surface of which a suitable decorative finish may be applied. The covers and envelopes are generally of the same outer configuration. This configuration can be best seen in Fig. 1. The covers and envelopes may be permanently secured together at one edge 8, as by rivets 10a, 10b or by staples, or the like; or they may be joined by some suitable, separable fastener, so that if it is desired to alter the number of envelopes after assembly, it is only necessary to remove the fasteners by which the covers and envelopes are joined.

Both the covers and envelopes have a fold line 12 adjacent and parallel to the edge 8, so that the album may be opened and closed easily. The

portion of the covers and envelopes between the fold line 12 and the edge 8 constitutes a back 20 for the album. The back is formed with slots or recesses 21a, 21b and projections 22a, 22b, extending therefrom, as best seen in Fig. 1.

The backing member 6 is made of a sheet of material formed into a tube. One edge 14 of this sheet is provided with a pair of overlapping portions 18a, 18b which overlap the opposite edge 16 along the marginal portions thereof. However, the two edges 14 and 16 are spaced from each other so as to form a slot 19 to receive the back 20. The overlapping portions 18a, 18b of the backing members are of flexible material; they grip the projections 22a, 22b of the back in clutching relation, and lock in the slots or recesses 21a, 21b so that the backing member holds firmly to the back. The assembled album thus assumes a pleasing appearance, and details of the assembly and binding are not immediately visible.

In the preferred embodiment, the backing member is made of a transparent plastic material, such as that known commercially as "Lucite." This material is flexible, as well as transparent, so that the backing member 6 and its overlapping portions 18a, 18b are all made in one piece of the same material.

A title-bearing slip 24 may be simply inserted within the tubular backing member, and may be changed if it is desired to use the album for a collection of articles distinguished by a different title. If desired, only the outer portion of the backing member need be of transparent material. The backing member may be made of other material, for example steel, in which case the title-bearing slip may be attached to the outside of the tube.

Each envelope 4a, 4b, etc. is preferably made of stiff paper or other flexible material, and in the preferred embodiment each envelope is open at its top edge 26. Leading from each edge 26 of each envelope is a separation 28 therein, such as a slit, a perforation, a notch or the like. A fold line 32, communicating with the slit 28, leads to another edge 30 of the envelope. In the preferred embodiment, the fold line 32 and slit 28 are on both faces 34 and 36 of the envelope. These fold lines constitute hinges and thereby create foldable flaps 34a and 36a, opening away from each other, which enable the articles within the envelope to be easily removed therefrom and replaced therein. It will be observed that by this means there is no danger of the record or other fragile article being broken, as there would be if the article were merely grasped at a thumb opening, as in the conventional article-containing album.

The fold lines 32 are preferably treated with a reinforcing material 38 which stiffens them and causes the flaps to assume their open position when the album is opened, and to retain that position as long as the album remains open. This may be best seen in the perspective view shown in Fig. 6.

The open edge 26 of each flap 34a, 36a may be turned inwards to a depth of approximately one-sixteenth of an inch, so that when the envelope is in a closed position, the flaps meet in a line and thereby provide a cover for the article contained therein, in this simple manner prohibiting the entry of dust and other extraneous matter.

The position which an article, for example a record 40, will assume within the envelope is shown in Figs. 1 and 6. Each envelope may be

provided with a central opening 42, so that the title of the article contained therein may be seen without removal of the article from the envelope.

There has thus been described an album of particularly simple construction and pleasing appearance, which may be assembled and disassembled with ease, and wherein the number of article-holding units may be varied at pleasure. The title of the album may be easily changed to correspond to the articles to be contained therein, and means are provided for facilitating the removal and replacement of such articles with ease, and with a minimum of danger from breakage.

Although only one embodiment of the invention has been shown, it will be apparent to those skilled in the art that albums constructed in accordance with the invention may take other forms, and yet remain within the scope of the invention. Thus, while the tubular backing member has been shown as being provided with a pair of overlapping marginal portions, it may have but one overlapping portion, for example, in the center. Similarly, the slots or recesses 25 in the back of the album and the projections therefrom may take different forms from those illustrated.

The slit 28 or other separation, although convenient, may be omitted if desired; and the fold line 32, instead of being angularly disposed in relation to the edges 26 and 30 of the envelope, may be disposed differently; for example, it may lead from one edge of the envelope across to the opposite edge thereof.

What we claim is:

1. An article-holding album comprising a pair of outer covers and including at least one envelope between said covers for holding said article, said envelope and said covers being secured together at one of their edges, said envelope being constituted of stiffened flexible material and being open along at least one other edge thereof and having a fold line extending from a point adjacent said open edge to a point adjacent a third edge of said envelope, whereby to provide a flap which automatically opens when said covers are swung apart.

2. The article of claim 1 in which the material along said fold includes a reinforcing substance for further stiffening said material.
